C. T. RASCHICK

CHECK HOLDER AND CUTTER

Filed Feb. 2, 1920

Patented Feb. 19, 1924.

1,483,910

UNITED STATES PATENT OFFICE.

CHARLES T. RASCHICK, OF ST. PAUL, MINNESOTA.

CHECK HOLDER AND CUTTER.

Application filed February 2, 1920. Serial No. 355,572.

To all whom it may concern:

Be it known that I, CHARLES T. RASCHICK, a citizen of the United States, residing at St. Paul, in the county of Ramsey and State 5 of Minnesota, have invented a new and useful Improvement in Check Holders and Cutters, of which the following is a specification.

My invention relates to a check holder and 10 cutter which is particularly designed to hold a pad of checks in a convenient manner so that the checks can be removed from the stub of the pad as they are desired for use and punched by the cutter associated there- 15 with without requiring an extra punch for making indications by serrations or cutaway portions in the checks of the pad.

An essential feature of my invention is to 20 provide a cutter for punching indications in the checks when they are removed from the pad, the cutter being placed to operate conveniently in relation to the holder and pad of checks so that the cutter can be readily operated. The holder and cutter is 25 designed to be carried on a suitable hook or fastening, which engages it at one end thereof. The peculiar, yet simple design or my holder and cutter allows the same to be conveniently used without removing it 30 from the hook or holding means by which it is attached to the person operating the same. The cutter is disposed at the opposite end of the holder from the carrying loop so that when the holder is in use the 35 cutter hangs downward in a convenient position so that it can be engaged and operated.

A further object of my invention is to 40 provide a pocket associated with the cutter to enclose and hold the clippings from the checks, and the cover of the pocket being freely slideable so as to move the same by gravity into closed position when the holder hangs by the holding loop on the operator's 45 person, it also being a feature of the invention to provide means whereby the checks normally hold the cover of the pocket in closed position.

An object of my invention is to provide 50 a peculiar shaped cutter or punch, which is of a simple, inexpensive design, yet very effective in making a clean-cut punch or serration in the check. The female portion or opening of the cutter punch extends angularly in relation to the cutting or punching tongue, which causes only a small portion

of a ticket to be engaged and cut or punched in the start of the operation of the punch to shear or cut the ticket in accordance with the shape and design of the punch cutter. 60 This feature with the angular positioning of the female portion of the cutter punch allows a clean-cut punch to be made without necessitating the male portion of the punch fitting exactly the female portion and necessitating sharp edges on both of the same. 65

Another object of the invention is in the natural guard, which is formed for the point or cutting end of the tongue portion of the punch by the angularly positioned female portion thereof and also to provide a guard over the cutting point to limit the upward movement of the same and form an additional guard for the sharp pointed end of the cutter and at the same time to form a 70 gage to limit the depth of the cut in a ticket when the punch is desired to cut a notch out of one of the tickets to indicate an amount. 75

In the drawings forming part of this 80 specification:

Figure 1 is a perspective view of my check holder and cutter as it would appear in use holding a pad of checks.

Figure 2 is a cross sectional side elevation 85 of my device.

Figure 3 is a perspective view of the upper portion of my device.

Figure 4 is a cross section on the line 4-4 of Figure 2. 90

Figure 5 is a perspective view of the lower portion of my device, illustrating an alternative form of cutting punch with the cover of the pocket in open position.

Figure 6 is a view of a portion of a check. 95

In the drawings A represents my check holder and cutter, which is designed to hold a pad of checks B, which are stapled together on one end in the ordinary, well-known manner, with the stub ends 10 of the checks held 100 between the gripping face or plate 11 and the back 12 of the holder A.

The face 11 is formed as an extension from the back 12 and extends approximately parallel thereto, being connected with 105 the same by the upper end portion 13, to which is attached the holding loop 14 by the cleats 15, or in any other suitable manner. The holding loop 14 is engaged by a hook, chain or other suitable means, not 110 shown, for attaching the holder A to the belt of a waitress or clerk in the use of the

same, while the body portion or back 12 hangs free, either extending in a downward direction or so that it can be readily engaged and elevated to remove one of the checks 16 from the pad B. The checks 16 are perforated or otherwise suitably scored at 17 to allow them to be easily disengaged from the stub portion 10 of the pad.

Engaging teeth 18 are formed on the front 10 edge of the plate 11, while a spring 19, which is attached to the back 12, tends to hold the pad B into engagement with the teeth 18. Guide flanges 20 are formed depending from the engaging plate 11, while 15 reinforcing flanges 21 project upward from the back 12 to form side engaging members to hold the pad in line in the holder A with its checks extending along the back 12.

A cutter punch C is carried by the end of 20 the holder A opposite to the loop 14 and is provided with a cutting tongue 22, which is formed of spring steel, or other suitable material, which is attached to the plate 23 at 24 to the upwardly projecting flange 25, which extends as a portion of and approximately at right angles to the body portion 25 of the plate 23. The plate 23 forms the back and body portion of the cutter punch C and also the cover for the pocket E, which is 30 formed as an integral portion and extension of the back 12.

The plate 23 is held freely slidable to the back 12 by the inturned flanges 26, see Figure 4, which engage along the lower, longitudinally extending edges of the back 12, while the back 12 is cut away or formed with longitudinally extending recess portions 27, to form a narrow portion at 28 along the back 12 of the holder. This narrow portion 40 28 allows of free engagement of the checks 16, particularly when the pad B becomes practically used up and only a few checks remain in the pad, and also allows the cutter plate 23 to be removed by depressing the tongue shoulder 29, which is formed by cutting a portion out of the back 12 and bending it upward to normally engage against the flange 25 of the cutter to limit the backward movement of the same. This 45 construction allows a new cutter tongue and blade to be provided for the holder A at any time, should it be found necessary to do so and this feature is of great importance in the practical development of my invention. 50 Stiffening ribs 30 are formed extending longitudinally in the portion 28 to strengthen and add to the rigidity of that portion of the back, to properly support the elements of the holder.

60 The plate 23 is formed with an upwardly inclined end 31, which extends at an obtuse angle from the body portion of the plate and forms a cover for the upwardly projecting portion 32 of the pocket E. An opening 33, 65 which is of the same shape and of a slightly

larger dimension than the cutting end or point 34 of the cutting tongue 22, is formed in the angularly extending portion 31 of the plate 23, while the rear portion of the opening 33 extends into the body portion of the 70 plate 23 and is of any suitable shape. In this construction the cutter tongue of the punch C is formed with an enlarged finger engaging portion 35, which limits the downward movement of the cutter tongue 22 in 75 the opening 33.

A loop member 36 is secured to the angular portion 31 and through which the pointed cutting end 34 of the tongue 22 extends. The loop 36 forms a guard and limits the upward movement of the cutting end of the tongue 22 as it prevents the sharp pointed end 34 projecting or being bent upward into a dangerous position. In a device of this kind it is necessary that no portions of the 80 same be exposed upon which the operator can be easily injured. The guard 36 will protect the point 34 while also the upwardly projecting end 31 of the cover forms a natural guard for the pointed cutting end 34. 85 The loop 36 also forms a stop or gage for the checks 16 to limit the depth of the cut or cutter punch C in the checks.

In the construction of cutter punch illustrated, a V-shaped cut is punched from the tickets or checks 16, such as 37, illustrated in Figure 6, to indicate the amount of a purchase or amount to be paid to the cashier. It is obvious, however, that the shape of the 90 cut or opening to be punched into the checks 100 can be of any other desirable shape or nature.

In operating the cutter punch C, a ticket or check 16 taken from the pad B is inserted with its edge against the gage 36 and a portion of the check positioned between the point of the cutter 34 and the upper end of the opening 33 in the portion 31 of the plate. As the cutting tongue 22 is depressed, the point 34 will first pierce the check and then shear a V-shaped portion out of the same at a point on the check to indicate the amount of a purchase, while the portion of the check clipped or punched from the body of the same will be deposited into the chamber 38 of the pocket E and retained therein until the pocket is opened by pulling the punch with its plate 23 backward to draw the portion 31 back sufficiently to open the same.

The plate 23 with the portion 31 is held freely slidable by the flanges 26 to the back 12 of the holder and thus when the holder is in use and the pocket E hangs downward the plate 23 would move or be held by gravity into closed position. However, the 120 checks 16 of the pad B engage against the flange 25 and form a stop to hold the cover of the pocket E normally in closed position. In this manner the flange 25 performs two 125 functions, as it also tends to hold the pad 130

B in place along the back 12. The cover of the pocket can be opened, however, even with the pad of checks B in place in the holder, by pulling backward against the checks to 5 bend them sufficiently to allow the cover to move into open position.

In Figure 5 a cutter punch F is illustrated, having a cutting tongue 39 formed out of the body portion of the plate 23, the 10 pointed end 40 of which coincides with the similar shaped opening 41 formed in the angularly disposed end 31 of the plate 23. The functions of this cutter punch are identical to those performed by the cutter punch 15 C and this punch operates to cut a portion from the checks to indicate the amount of a purchase and deposit it in the pocket E formed on the lower end of the back 12.

In the operation of a device of this nature 20 the general construction of the holder is practically indestructible with ordinary use and care but it is very desirable to have a replaceable cutter, as through continued use the cutter is apt to become dull and owing 25 to the simple, inexpensive construction of my device a new cutter can be quickly and easily attached to the holder by sliding the plate 23 backward, when the pad of checks B is removed from the holder and the spring 30 tongue 29 depressed to allow the engaging flanges 26 to move back to the narrowed portion 28 of the back 12, whereupon the flanges 26 are disengaged from the back to release the cutter punch plate and cover for the 35 back 12. This feature adds materially to the practical nature of my device.

The inclined or angularly positioned portion 31 of the plate 23 permits the cutter tongue 22 to operate easily to make a clean-cut notch in the tickets or checks and the construction does not require the close fit 40 between the male and female portions of the cutter punch as are necessary in the ordinary punching devices.

45 The stub 10 of the pad B, which is left clamped between the back 12 and the plate 11, after all of the tickets or checks 16 have been removed can be easily removed either by engaging the same through the opening 50 42 formed in the plate 11 to depress the stub and free it from the teeth 18 so that it can be pulled out and discarded or the stub can be engaged between the flanges 20 and 21 on either side of the same and released by 55 depressing against the spring 19. A new pad of checks can then be inserted in the holder while the back of the same holds the spring 19 depressed, the spring 19 holding the stub of the pad into engagement with 60 the teeth 18 and plate 11 while the leaves or checks of the pad form a stop to hold the cover plate 23 in closed position on the pocket E.

65 The positioning of the pocket E at the opposite end to the holding loop 14 is an essen-

tial feature of the construction of my device, as it allows the cutter punch C to be operated without removing the holder A from the chain or hook which holds it by the loop 14 to the waitress's or clerk's belt, it being 70 easy for the clerk or waitress to engage the end of the holder carrying the pocket and raise it sufficiently to readily see and operate the cutter punch.

In accordance with the patent statutes I 75 have described the principles of operation of my invention, together with the apparatus which I now consider to represent the best embodiment thereof, but I desire to have it understood that the construction shown is 80 only illustrative and that the invention can be carried out by other means and applied to uses other than those above set forth within the scope of the following claims.

I claim—

1. A punch comprising a body member having an inclined wall positioned at the end thereof with an aperture therein, a tongue mounted on said body member extending along said body member having 90 a portion adapted to engage the aperture in said inclined wall and a pocket beneath said inclined wall, free of said body member, for retaining the cuttings from said punch.

2. A punch comprising a flat body portion, a shearing tongue formed in said body portion, and an inclined wall formed on one end of said body portion extending angularly outwardly therefrom in close 100 proximity to the cutting point of said tongue and having an opening adapted to receive the cutting point of said tongue in a manner to pierce and shear a check inserted between said cutting tongue.

3. A check marking device comprising a support and check marking means detachably mounted on said support and removable in its entirety therefrom.

4. A notching device comprising a shearing tongue extending approximately flat throughout its length and provided with diverging cutting edges and a bent plate extending in close proximity to the pointed end of said shearing tongue and provided with an opening adapted to be progressively engaged by said shearing tongue.

5. A notching device comprising a cutting tongue extending approximately straight throughout its length, a member positioned beneath said tongue having an opening adapted to progressively receive the cutting point of said tongue, said member being bent across the opening formed therein to position a portion thereof in close proximity to the point of said cutting tongue.

6. A marker for a pad of checks comprising a body member, a pocket mounted thereon having upwardly inclined side walls, a cover plate slidably mounted on said body

member and having an angularly disposed closure portion adapted to engage said side walls of said pocket to close the same, and punching means mounted on said cover.

- 5 7. A notching device formed out of a single piece of material having a notching tongue struck therefrom relatively flat throughout its length and a notched plate formed thereby, said notched plate being 10 bent away from said tongue at a portion thereof and having a pointed end bent towards the point of said tongue to progressively engage the same as the tongue is forced towards the plate.
- 15 8. A marker for a pad of checks comprising a body member, a pocket mounted thereon having upwardly extending side walls, a cover plate slidably mounted on said body member and having an angularly 20 disposed portion engaging said side walls of said pocket, said inclined portion being formed with an opening and a cutting tongue mounted on said cover having a portion cooperating with said opening for discharging cuttings therethrough into said pocket.
- 25 9. A notching device including a pocket having an upwardly extending portion in relation to the back of said device, a slideable plate having an angularly positioned portion adapted to cover the upwardly projecting portion of the open end of said pocket, a cutting tongue associated with said plate and an opening formed in said angularly positioned portion of said plate which is adapted to receive the cutting end of said tongue to clip a portion from a check in the act of punching and deposit the clipping into said pocket.

- 30 10. A punch including a slideable plate, a punching tongue carried by said plate, an angularly extending portion formed on said plate, a recess formed in said angularly positioned portion to receive the cutting portion of said tongue and a guard gage adapted to limit the upward movement of said cutting tongue and to project above the cutting end of said tongue to form a guard for the same and a gage to limit the depth 45 of the cut from the edge of a check.

- 50 11. In combination with a support, a punch, a pocket associated with said punch, slideable means adapted to support said punch, said supporting means forming the cover for said pocket, and said slideable means, together with said punch, being removably held to said support.

- 55 12. A check notching device comprising

a plate, a cutting tongue attached to said plate having a pointed end, an aperture in 60 said plate adapted to cooperate with said cutting tongue and a looped guard positioned around the end of said tongue inwardly from the extreme point thereof and attached to said plate, said guard serving 65 as a stop for gauging the depth of cut of said cutting tongue.

13. A cutter punch, including a plate, a flat cutting tongue associated with said plate, said tongue being adapted to extend 70 at an angle to said plate, a pointed cutting end formed on said tongue, an angularly disposed end formed on said plate and an opening formed in said angularly disposed portion of said plate adapted to coincide 75 with the cutting point formed on said tongue to pierce and shear a portion from a check or ticket in the operation of said punch.

14. A cutter punch, including a plate-like body portion, a cutting tongue extending from said body portion, an angularly disposed portion extending from said body portion, an opening formed in said angularly disposed portion and extending into 80 said body portion, said angularly disposed portion of said body portion extending in close proximity to the cutting free end of said cutting tongue and said opening therein being adapted to coincide with the cutting end of said tongue to cause the cutting end of said punch to first pierce and shear in the act of punching.

15. A punch formed of thin, flat material, including a cutting tongue, an angularly disposed portion formed on the body portion of said punch, an opening formed in said angularly disposed portion adapted to coincide with the cutting end of said tongue to cause the cutting end of said tongue to coincide at an angle with the sides of said opening to cause a shearing action in punching and a guard for the cutting end of said tongue adapted to limit the upward movement of the same.

16. A punch formed of thin, flat material, in combination with a holder, including a plate-like body portion, an angularly disposed portion formed on said body portion, an opening formed in said angularly disposed portion and a cutting tongue having a cutting end which is adapted to coincide at an angle with said opening in said angularly disposed portion.

CHARLES T. RASCHICK.
